UNITED STATES PATENT OFFICE.

EARLE M. BARROWS, OF MINNEAPOLIS, MINNESOTA.

SHOTGUN SHELL.

Application filed January 20, 1919. Serial No. 272,130.

To all whom it may concern:

Be it known that I, EARLE M. BARROWS, a citizen of the United States, resident of Minneapolis, county of Hennepin, State of Minnesota, have invented certain new and useful Improvements in Shotgun Shells, of which the following is a specification.

The object of my invention is to provide a shot or scatter-gun shell which has contained within itself a tracer projectile or capsule, distinct or independent from its ordinary load of shot, which projectile or capsule is so designed that upon firing it will accurately follow the center of trajectory or pattern of the multiple shot charge and leave a trail of fire, smoke or vapor in the air to indicate the path traversed by the shot charge and enable the person using the gun to correct any inaccuracy of aim.

A further object is to provide a shot or scatter gun shell which has contained within itself a tracer projectile or capsule, distinct from and independent of its ordinary load, which projectile or capsule is so designed that upon firing it will accurately follow the center of trajectory or pattern of the multiple shot charge and at a certain predetermined range or distance from the muzzle of the gun, will give forth a burst of fire, smoke or vapor in the air to indicate the path in which the shot charge is traveling, and so also indicate by comparison with the point at which the burst is discernible the range or distance of the target or object from the person using the gun and enable such person to correct inaccuracy of aim or misconception of range.

A further object is to provide a shot load designed for use for either field, target or wing shooting purposes.

Other objects of the invention will appear from the following detailed description.

The invention consists generally in various constructions and combinations, all as hereinafter described and particularly pointed out in the claims.

In the accompanying drawings forming part of this specification,

Figure 1 is a sectional view of a shot gun shell embodying my invention,

Figure 2 is a sectional view of a modified construction of the wad and projectile or capsule,

Figure 3 is a sectional view of another modification,

Figure 4 is a sectional view of still an-

other modification of the wad and projectile or capsule, showing a form of superimposed wad,

Figure 5 is a sectional view of still another modification of Figure 2,

Figure 6 is a horizontal sectional view of Figure 3 on the line 6-6 of Figure 3.

In the drawing, referring to Figure 1, 1 represents the paste-board shell-case of a standard shell. 2 represents the brass shell base, 3 the base wad, 4 the primer, 5 the powder space and powder, 6 the shot space and shot, and 7 the shot wad. 8 represents the powder wad, of felt or other fibrous material, which will expand or contract in passing through the barrel of the gun. 9 represents the metal projectile or capsule. 10 is a weight of lead or other heavy metal in the projectile or capsule. 11 is the smoke composition, preferably of gunpowder, an oxidizing agent, magnesium, and a binding agent such as shellac, but any other material for accomplishing the same result may be used. 12 is a fuse or slow match, preferably of porous paper, impregnated with saltpeter, but any other material for accomplishing the same result may be used. 20 is a shoulder on the projectile or capsule, designed to reduce gas leakage and giving a greater bearing against the shot charge.

Upon the discharge of the shell through the action of the primer 4 the powder ignites, producing a large volume of gas and great heat. This presses the wad 8 and the projectile 9 forward, carrying the shot 6 and shot wad 7 before them. The resistance of inertia of the shot charge holds the tracer projectile 9 in place in the wad 8, the two forming a piston in the barrel of the gun 25 acted on by the pressure of exploding powder of the shot charge. The heat of the discharge ignites the fuse or slow match 12. As the shot charge reaches the muzzle its full speed is attained and its resistance of 100 inertia becomes zero. At the same time the choke of the gun barrel and the friction thereof retards the wad 8 and the tracer projectile 9, having no more resistance from the shot charge, leaves its bore in the wad, 105 impelled partly by its inertia and partly by the pressure of the expanding powder gases, and follows the trajectory of the multiple shot charge.

At a point in the flight of the tracer projectile, predetermined by the length and composition of the slow match or fuse,

which has been ignited by the burning powder charge, the fire therein reaches and ignites the smoke composition which becomes visible through a trail or burst of smoke 5 or fire so that the person using the gun can readily determine the direction of the discharge and by comparison with the point already known at which the tracer trail or burst appears, can determine with accuracy 10 the range of the target. In this invention I do not, however, confine myself to the use of a range indicating slow match or fuse, as it may be omitted and the tracer composition ignited directly from the main powder 15 charge, and being of slow-burning composition, leave a continuous trail during the flight of the tracer projectile, or the slow match or fuse may be cut down so as to merely delay the ignition of the smoke 20 composition, so that there will be no smoke therefrom near the muzzle of the gun to obstruct the vision of the marksman.

In Figure 2 I have shown a modified construction of the wad and tracer projectile in 25 which 11^a represents the space to be filled with the smoke compound or the compound and fuse. The shoulder 20 of the metallic tracer projectile 9 is here shown recessed into the wad 8. The weight 10 in the tracer 30 projectile of lead or other heavy metal is designed to aid in the flight of the tracer projectile and to prevent it from tumbling. 13 is a metallic cylinder attached to the wad 8 and designed to produce a more perfect 35 bore from which the tracer projectile 9 is fired. The hollow cylinder or bore lining is provided with a shoulder 14 to aid in holding it in position in the wad 8.

Figure 3 shows a modification of Figure 40 2, in which the shoulder or rim 20 on the tracer projectile is omitted. The metal bore 13 is further provided with spiral groove rifling 15 into which fit projections 16 provided on the tracer projectile. Upon discharge of the tracer projectile the grooves or rifling sets the tracer projectile spinning or rotating on its longitudinal axis and tends to increase its accuracy and prevent tumbling.

50 In Figure 4 the weight 17 is made integral with the tracer projectile 9^a. Shoulders 18 are also provided at the base of the tracer projectile to reduce the size of the opening into the smoke composition chamber and 55 prevent too rapid combustion of the smoke composition. A fuse or slow match is also shown, but may be omitted. The shoulders on the cylindrical metallic bore are also omitted, the bore being held in place in the 60 wad 8 by a suitable glue composition or by compression. There are also shown wedge-shaped wads 19 and 19^a, imposed above the wad proper 8 and its tracer projectile 9^a. These are for the purpose of reducing gas 65 leakage. Upon reaching the choke of the

gun barrel the greater friction and resistance on the thick edges of the wad causes the thin edges to turn outward in a hingelike manner, allowing the tracer projectile 9^a an unobstructed flight. These wads may be 70 superimposed on any of the designs shown, there being no change produced thereby in the mechanical operation of this invention as in the case of the plain wads. The heavier tracer projectile drives them out of the way 75 without seriously being deflected in its flight.

In Figure 5 I have shown a modification of Figure 2, with the wad 8, the tracer projectile 9 and the shoulders 20, the weight 10, the smoke compound chamber 11^a, the metallic bore 13 and shoulders 14, and it is also provided with indentations 21 cut in the base of the tracer projectile 9. These may be varied in shape and are designed to steady the tracer projectile in its flight in 80 85 the same manner as the feathering of an arrow.

In various ways the device herein described may be modified and the parts shown may be combined and still be within the 90 scope of my invention.

I claim as my invention:

1. A device of the class described comprising a wad, a tracer projectile mounted therein and having a chamber adapted to contain a combustible composition, said projectile having means to aid its flight and prevent tumbling.

2. A device of the class described comprising a jacket adapted to fit within a shot gun shell, a projectile encircled by said jacket and having a weighted end, and a chamber adapted to contain a suitable combustible composition.

3. A device of the class described comprising a jacket adapted to fit within a shot gun shell, a projectile encircled by said jacket and having a closed end and a weighted portion adjacent said end, said projectile also having a chamber therein adapted to contain a combustible composition.

4. A device of the class described comprising a wad adapted to fit a shell, a tracer projectile mounted therein and having a chamber adapted to contain a combustible composition, and a time fuse mounted for communication with said chamber.

5. A device of the class described comprising a wad adapted to fit a shell, a tracer projectile encircled by said wad and having a closed weighted end and a chamber adapted to contain a combustible composition, and a fuse closing the entrance to said chamber.

6. A device of the class described comprising a wad adapted to fit a shell, a tracer projectile mounted in said wad and having a closed outer end and an open inner end, said projectile having a chamber therein adapted to contain a combustible material accessible through the open end of said chamber, and

- a time fuse fitting within said open end and normally closing the same, said fuse communicating with said composition.
7. A device of the class described comprising a wad adapted to fit a shell and having an orifice therein, a tracer projectile fitting within said orifice and having a chamber adapted to contain a combustible composition, and means for delaying the ignition of said composition.
8. A device of the class described comprising a wad adapted to fit within a shell, a tracer projectile mounted in said wad and having a chamber therein adapted to contain a combustible composition, and means mounted on the outer end of said wad and composed of sections adapted to separate from the projectile when the projectile is discharged.
9. A device of the class described comprising a wad adapted to fit within a shell, a tracer projectile mounted in said wad and having a chamber therein adapted to contain a combustible composition, and wedge-shaped discs placed face to face on the outer end of said projectile, for the purpose specified.
10. A device of the class described comprising a wad having an orifice therein, a tracer projectile fitting in said orifice and containing a combustible composition, said projectile being mounted for separation from the wad before said projectile leaves the gun muzzle.
11. A device of the class described comprising a wad, a tracer projectile mounted therein for separation therefrom after the wad has passed out of the shell, said projectile having a weighted forward end for directing its flight and containing a combustible composition, with means for delaying the ignition of such composition.
12. The combination with a shot gun shell, of a wad fitting therein between the space reserved for the powder charge and the space reserved for the shot charge, a tracer projectile mounted in said wad for separation therefrom, and having means for directing its flight and adapted to contain a combustible composition.
13. A shot shell having a tube, a powder-charge and a shot-charge located therein, a wad interposed between the said charges and an ignitable flight-marking body installed in the said wad in position to be ignited by the powder-charge at the explosion thereof and separable from the wad and of sufficient carry to follow the shot-charge, and mark the flight thereof.
14. A shot shell having a paper tube, a powder charge, a shot charge, a plurality of wads interposed between the said powder charge and the said shot charge, and a flight-marking pellet or body installed in the rear-most wad which is imposed directly upon the said powder charge, adapted to be ignited by the explosion of the powder charge separable from the said rearmost wad and of sufficient carry to follow the charge of shot.

In witness whereof, I have hereunto set my hand this 17th day of January, 1919.

EARLE M. BARROWS.
